UNITED STATES PATENT OFFICE.

OTTO W. SCHAUM, OF PHILADELPHIA, PENNSYLVANIA.

MACHINE FOR PUNCHING HOLES IN JACQUARD CARDS.

SPECIFICATION forming part of Letters Patent No. 445,340, dated January 27, 1891.

Application filed April 21, 1890. Serial No. 348,808. (No model.)

To all whom it may concern:

Be it known that I, OTTO W. SCHAUM, of the city and county of Philadelphia, State of Pennsylvania, have invented a certain new and useful Improved Machine for Punching Holes in Jacquard Cards, of which the following is a true and exact description, reference being had to the accompanying drawings, which form a part of this specification.

10 My invention relates to machinery for punching the holes in Jacquard cards; and has for its object to improve such machinery and render it more easy and convenient to operate.

15 My improvements will be best understood as described in connection with the drawings, which illustrate the construction of a machine embodying them, and in which—

Figure 1 is a perspective view of the said machine. Fig. 2 is a perspective view of the rods or punches used to force the locking-bolts back to an inoperative position, and their attachments. One of the punches which operate upon the card, the bolt which secures 20 the said punch in operative position, and the key by which the bolt is operated are also shown. Fig. 3 is a plan view of my improved machine, taken on the section-line $y-y$ of Fig. 5, or along the top of plate D, said plate being also broken away, as indicated by section-lines, to show some details of construction. Fig. 4 is a side elevation of the machine, taken on the line $w-w$ of Fig. 5; and Fig. 5 is a front elevation taken on the line $x-x$ of Fig. 4.

25 A is the frame of the machine; A', the table before which the operator stands; B B', plates secured one above the other, and having a recess b^2 formed between them to receive the cards. The plates B and B' are perforated, 30 as shown at b and b' , so as to permit the punches to pass through them.

As shown, the plates B B' are secured together by means of the threaded bushings C C, and they are fastened to the pad or frame 35 of the machine in any convenient way.

40 D D' are two iron plates, which together form the movable head of the machine. This head is formed with a series of vertical perforations d d' , corresponding in position with the perforations b b' in the plates B B'. The 45 parts d' of these perforations are smaller in

diameter than the parts d . Sockets d^2 are formed at each end of the movable head to receive punches, which are secured therein so as to always move up and down with the 55 movable head. Leading into the perforations d are two series of horizontal perforations or holes, one series, indicated by the letters d^3 , leading from the back of the movable head, and the other series, indicated by the letters d^4 , leading from the front of the movable head.

As shown, the two plates D and D' are secured together by means of the guide-rods E E, which pass through perforations d^5 d^6 in 60 the said plates and clamp them together by means of the rings e, resting against the lower plate D, and nuts e' , screwing on threaded ends of the rods E and pressing against the upper part of the plate D'. These guide-rods E 65 move in the bearings C of the lower head B B', keeping the movable head in line with it. Horizontal perforations d^7 d^8 are also formed in each end of the movable head, for the purpose hereinafter described. The movable 70 head is actuated by means of pitmen or connecting-rods F F, secured to it, as shown, and the cams G G, attached to the driving-shaft H. The shaft H is driven by the pulley I and clutch J. The said pulley runs loosely upon 75 the shaft H, except when the clutch J is actuated so as to connect them.

I have not thought it necessary to describe the construction of the clutch shown, as any convenient clutch may be used and arranged 80 so as to normally disconnect the pulley and shaft and to connect them only when the clutch-actuating device such as is indicated at J' is operated.

K K, &c., are the card-punches formed with 85 an enlarged head k and proportioned so that the punches will pass freely through the perforations d' , while their heads will rest upon the rim formed between the perforations d and its enlarged continuation d . The portion d of the perforation is sufficiently long 90 to permit the punches to move up in it for a distance sufficiently great to prevent their ends passing through the slot b^2 when the movable head is in its lowest position.

100 M M, &c., are bolts, which are inserted in the perforations d^4 in the movable head.

They are formed with an offset m , which, by engaging with a bar m^3 , secured across the lower part of the perforations d^4 , will prevent them coming out of said perforations, and in 5 order to prevent them from moving too freely in the perforations, I form in each bolt a recess m^7 , in which I place a light spring m^8 , which presses against the upper part of the perforations d^4 and serves to steady the bolt 10 therein.

L L, &c., are rods which pass through the perforations d^3 in the back of the movable head and at their rear ends are secured to a bar L' , from each end of which rods $L^2 L^3$ project and pass through the perforations d^7 in 15 the movable head. On the end of the parts L^3 of these rods, which project to the front of the head handles L^4 are secured, and about said parts L^3 , which are, as shown, smaller 20 than the parts L^2 , spiral springs L^5 are secured, which act to press the rods and the bar L' , which they carry, backward.

To the extent above described the machine in its general features is old, and my present 25 invention consists of the hereinafter-described improvements upon the said machine. To the upper part of the movable head I secure one or more rods $n n'$, preferably two, arranged one in front of the other, as shown. 30 They are attached to the movable head by means of the brackets $N N$, and I pivot upon these rods keys $O O'$, the lower ends of which rest against the ends of the bolts M , while their upper ends are properly formed to enable them to be operated—as, for instance, 35 like a type-writer—and it is preferable to arrange these keys on the rods $n n'$ alternately, so as to give them the staggered arrangement shown, by which the apparatus is rendered 40 more compact and more easily operated. Each of the keys will of course be marked to indicate the bolt and punch which it controls.

The operation of the machine is as follows: 45 The operator sets the machine for the work it is to perform by pressing down upon the keys which govern the punches which he desires to bring into operation. Each key, when pressed, pushes its corresponding bolt until its inner end extends across the top of the 50 perforation d and above the head k of the punch contained in said perforation. The desired pattern of the card having thus been provided for, the operator slips a blank card into the groove b^2 , and then by actuating the clutch- 55 lever J' connects the driving-pulley I with the shaft H , so as to rotate said shaft, and by means of cams G and connecting-rods F draw down the movable head. As the head moves 60 down, the punches K of course move with it until they come into contact with the blank card, when those punches over which the bolts M extend pass through the card, while those which are not bolted are free to rise in the perforation d , and do rise therein as the mov-

able head descends, making no perforation 65 through the card. The clutch is of course released after each card is perforated.

When it is desired to change the pattern, the operator takes hold of the handles L^4 and draws them forward, and, by means of the rods $L^2 L^3$ and the bar L' connected to them, the rods L are drawn into the perforation d , pressing against the ends of the bolts M , and pushing them back until their further motion is stopped by the engagement of their shoulders m with the stop-bar m^3 . 75

Having now described my invention, what I claim as new, and desire to secure by Letters Patent, is—

1. In a machine for punching holes in Jacquard cards, substantially as described, the combination, with the movable head having vertical perforations $d d'$ and horizontal perforations d^4 leading into the same, as described, punches K , passing through the perforations d' and having heads k situated in the part d thereof, bolts M , situated in perforations d^4 , and finger-keys O , pivoted to the movable head and with their ends resting against bolts M , all substantially as and for 90 the purpose specified.

2. In a machine for punching holes in Jacquard cards, substantially as described, the combination, with the movable head having vertical perforations $d d'$ and horizontal perforations d^4 leading into the same, as described, punches K , passing through the perforations d' and having heads k situated in the part d thereof, bolts M , situated in perforations d^4 , rods $n n'$, secured to the movable head, and finger-keys $O O'$, pivoted on said rods, as described, and so as to form two rows with a staggered arrangement and with their ends resting against the ends of the bolts M , all substantially as and for the purpose specified. 100

3. In a machine for punching holes in Jacquard cards, substantially as described, the combination, with the movable head having vertical perforations $d d'$ and horizontal perforations d^3 leading into the same, as described, punches K , passing through the perforations d' and having heads k situated in the part d thereof, bolts M , situated in perforations d^4 , finger-keys O , pivoted to the movable head and with their ends resting against bolts M , a bar L' , situated at the back of the head, having a series of rods L passing into perforations d^3 , rods $L^2 L^3$, secured to bar L' and passing through holes d^7 in the head, handles L^4 , secured to the end of rods L^3 , and springs L^5 , arranged to push the bar L' backward, all substantially as and for the purpose specified. 110 115
